UNITED STATES PATENT OFFICE

RUDOLF SOUKUP, OF RIVERSIDE, ILLINOIS

DESIGN FOR A BRACKET FOR DRAPERIES

Application filed June 7, 1929. Serial No. 31,593. Term of patent 7 years.

To all whom it may concern:

Be it known that I, RUDOLF SOUKUP, a citizen of the United States, residing at 274 Northwood Road, in the town of Riverside, county of Cook, and State of Illinois, have invented a new, original, and ornamental Design for a Bracket for Draperies, of which the following is a specification, reference being had to the accompanying drawing, forming part thereof.

Figure 1, is a plan view of a bracket for draperies showing my new and ornamental design.

Figure 2, is a side elevation of same.

Figure 3, is an end elevation of same.

I claim:

The ornamental design for a bracket for draperies as shown.

RUDOLF SOUKUP.
